(57) **CLAIM**

The ornamental design for a parking stop apparatus as shown and described.

DESCRIPTION

FIG. 1 is a front elevational view of a parking stop apparatus.

FIG. 2 is a rear elevational view of the parking stop apparatus of FIG. 1.

FIG. 3 is a left end elevational view of the parking stop apparatus of FIG. 1.

FIG. 4 is a right end elevational view of the parking stop apparatus of FIG. 1.

FIG. 5 is a top elevational view of the parking stop apparatus of FIG. 1; and,

FIG. 6 is a bottom elevational view of the parking stop apparatus of FIG. 1.

The broken lines are included for the purpose of illustrating portions of the parking stop apparatus and form no part of the claimed design.

1 Claim, 5 Drawing Sheets
